DESIGN FOR A PIN-UP ASH RECEIVER

Henry W. Louis, Cleveland, Ohio

Application November 6, 1946, Serial No. 134,563

Term of patent 3½ years

(Cl. D85—2)

To all whom it may concern:

Be it known that I, Henry W. Louis, a citizen of the United States, residing at Cleveland, in the county of Cuyahoga and State of Ohio, have invented a new, original, and ornamental Design for a Pin-up Ash Receiver, of which the following is a specification, reference being had to the accompanying drawing, forming a part thereof, in which:

Fig. 2 is a side elevation of the pin-up ash receiver;

Fig. 3 is a top plan view of the pin-up ash receiver.

I claim:

The ornamental design for a pin-up ash receiver, as shown.

HENRY W. LOUIS.
